UNITED STATES PATENT OFFICE.

EDMOND CAUDRELIER, OF PARIS, FRANCE.

MACHINE FOR THE MANUFACTURE OF TICKETS OR LABELS.

Application filed April 14, 1924. Serial No. 706,417.

To all whom it may concern:

Be it known that I, EDMOND CAUDRELIER, a citizen of the Republic of France, residing at Paris, in the Republic of France, 67 Avenue du General Michel Bizot, have invented certain new and useful Improvements in Machines for the Manufacture of Tickets or Labels, of which the following is a specification.

Machines of known types are employed for the manufacture of pasteboard tickets or labels for indicating the prices of goods, or for like purposes, by means of type characters with cutting edges which are adapted to cut out and to insert into the pasteboard a suitable paper whose colour corresponds to that of the characters desired.

My invention relates to a machine embodying this principle, but differing from the known machines by a new method of control and by the means employed for the stamping or embossing of the characters (letters and numerals) in the pasteboard. The stamping operation is of a progressive nature, i. e. the pasteboard-piece is printed or stamped by the successive formation of the several elements and in a continuous manner. For a given pasteboard piece, the operation can be performed with a small expenditure of power, which is also independent of the size of the said piece, or properly speaking, of its length, and hand control can be employed in all cases. In

addition to this advantage afforded in the manipulation of the machine, my said apparatus is susceptible of an adjustment by which the depth of the stamping will be constant throughout the series of pasteboard pieces, whilst in the known devices this depth chiefly depends upon the variable force employed in the manipulation of the hand-wheels or levers controlling the pressing plate.

My said pressing machine, as will be hereinafter described, requires no essential modification of the composing sticks and the ticket-holders in current use.

The appended drawings illustrate a constructional form of my said machine which is given solely by way of example and is employed for the stamping or pressing of pasteboard tickets or labels in a progressive

manner, the operation being continuous as well as adjustable. 55

Figure 1 is a front elevational view of the machine, and Figure 2 is a side elevation. Figure 3 is a plan view of the pressing plate. Figure 4 is a cross-section of a key of the said pressing plate. Figures 5 and 60 6 are respectively a cross-section and a plan view of a type holder for the type characters and Figure 7 is a plan of these holders and guides.

The said apparatus is constituted in 65 principle as shown in Figures 1 and 2 by a machine frame of substantial construction comprising three elements, viz., two cross-pieces B and a top plate C, the relative distances between the said elements may vary 70 for the purpose of adjustment, as will be further set forth. A screw V is inserted at each end into one of the said cross-pieces, and it has movable thereon a sliding carriage D having a screw threaded aperture; 75 said carriage is provided with two pairs of rollers, a lower pair G¹, and an upper pair G², revoluble respectively on the axles 1, 2. The upper rollers G² are in contact with the top plate C of the machine frame. The lower rollers are in contact with a movable 80 pressing plate P which essentially characterizes the present machine, and consists of a main body which is suitably cut out as shown in Figures 3 and 4 and wherein are 85 engaged a plurality of keys of identical construction.

The said keys whose cross-section is shown 90 in Figure 4 are in contact by their extremely thin ends 3 with the lower faces of the lateral recesses in the said pressing plate, the relative dimensions of the plate and the keys being such that the faces of the keys extend to a very slight degree above and below the top and bottom faces of the 95 said plate. For this purpose, a small space is allowed between the keys whereby they are given a certain freedom movement in the lateral direction. In like manner, the thickness of the end portions 3 is somewhat less than the width of the said lateral recesses in the pressing plate, so as to allow 100 a slight vertical movement of the said keys. The said pressing plate has at each end a ramp 4 followed by a flat portion 4' normally in contact with the lower rollers, and 105

an axial aperture 5 is pierced in each of said flat portions. When the machine is assembled, each aperture affords passage to a cylindrical tenon 6 mounted on the base 5 plate A and upon which is disposed a spring 7. A stop piece 8 secured to the cross-piece B prevents all ascent of the said pressing plate, but the latter can descend by compressing the spring 7. The screw V 10 is actuated for example by laterally disposed gearing E operated by a handle 9; obviously, any other suitable mechanical or electrical control may be employed without departing from the principle of the invention.

The said machine is completed, in the known manner, by a table 10 extending forwardly of the base A, the said table being provided with the parallel guides 20 where- 20 by the ticket-holder and the composing stick can be supported under the pressing plate. These guides 20 are carried by plates 24 slidingly mounted on posts 25 and yielding- 25 ly supported by springs 26 above the table 10.

The operation is as follows. The cross- 30 pieces B and the top plate C having been adjusted to the proper height, as will be further indicated, the composing stick is placed between the base plate A and the pressing plate P. By turning the screw V in the proper direction, the carriage D, which is supposed for example to be situated to the left of the machine, will move forward, and 35 the rollers G¹ will roll in the first place upon the straight portion 4'; but when the rollers come upon the ramp 4, the pressing plate will compress the left-hand spring 7 and will thus descend, also tilting to a 40 slight degree. As the said carriage continues to move, the lower rollers will approach the region of the keys t, the spacing of the 45 said rollers being such that they will rest completely upon the said keys without exerting upon the rigid side portion of the plate.

As the said rollers move forward, each 50 key is lowered in turn and is also given an alternate tilting movement i. e. when the rollers come upon the key and when they leave the same. The keys are enabled to move by reason of the freedom of motion which they possess in both directions, as above stated. The descent of a given key 55 provides for the stamping or pressing of the element of the ticket situated just below, by means of the composing stick.

It is observed that upon the descent of 60 the keys the lower faces of each key are successively brought into the same horizontal plane, and hence the pressing action is quite regular; on the other hand, the pressing action is progressive, and the total power required is made up of various small elements 65 of power corresponding to the descent of

a key, so that the effort upon the operating handle is accordingly reduced.

The first adjustment of the machine relates to the depth of the pressing operation. For pasteboard and coloured paper of a given thickness and for given characters (letters and numerals) it is obvious that this depth of pressure will depend upon the distance between the lower rollers G¹, and the upper flat surface of the base plate A. 70 75

For this reason, the distance between the cross-piece B and the said base plate is to be regulated. To this end the latter plate has at each of the four corners a steel block 11 serving as a nut for a screw 12 which supports the element B; a nut 13 engaging the portion 14 formed together with 11, serves (after adjustment in height) to screw the whole device in the tight position. The apertures 15, 16 are used with a claw wrench 80 or the like to obtain the rotation of the screw relative to its nut, and hence to raise and lower the member B having disposed thereon the rollers G¹.

Secondly, it is observed that the piece C 90 cannot be rigidly secured to the element B without exposing the screw V to flexion of an inadmissible value; this flexion might be due to a very small irregularity in the machine work upon the lower face of the top 95 plate which will have an effect upon the screw, through the medium of the upper rollers; on the other hand it is necessary to take up the wear of the parts.

The rollers G², should be brought into 100 contact with the top plate C upon which they are caused to bear; this can be carried out by adjusting the parts by means of the upper nuts (as further set forth), and the contact of said rollers with the said 105 top plate will prevent all flexion of the screw V.

For this double purpose, by an adjustment similar to the preceding, I am enabled to vary the distance between the top plate 110 C and the cross-piece B, by means of a screw 12' supporting the said top plate and co-operating with a screw-threaded portion of the said cross-piece. As in the preceding case, the whole device can be made tight 115 by means of a nut 13', after adjustment. By this double adjustment, the machine is particularly responsive both as to its operation and as to the range of depths of the embossing or stamping obtained. 120

For the first adjustment, the top plate C is brought near the cross-piece carrying the rollers G², this being a machine adjustment. For the second adjustment, the aggregate 125 of the top plate C and the cross-pieces B (provided with said rollers) is brought near the lower base plate A; this adjustment relating to the pressing action.

The parallel guides 20 are adapted to support the ordinary form of type holders or 130

a novel form thereof adapted to receive type of different sizes as shown in Figures 5 and 6. As shown therein, a type 27 may be supported for instance, for a capital letter, while a shorter type 28 may be supported by a different size of the holder as in Figure 7.

The said holders, which may have any desired width, comprise an upper plate 21 and an elastic member 22; the latter is secured to the edge of the said plate, and in this manner the said holder may be mounted upon one guide 20. The upper plate 21 has a certain thickness, and at the outer end it has an offset 23 supporting one end of the type character whereof the other end rests upon the parallel guide 20.

The thickness of the plate 21 is such that it takes up the thickness of the type character. When the pressure is brought upon the device, the whole aggregate is lowered; the said holder is arrested by reason of its thick edge, while the type character is brought down for the embossing or stamping action, and immediately after this takes place, the spring strip 22 comes into action and raises the aggregate comprising the said holder and the type character.

Having now particularly described and ascertained the nature of my said invention and in what manner the same is to be performed, I declare that what I claim is:—

1. In a stamping machine, a base, a co-operating pressure head, an interposed carrier, a series of independent pressing keys between said carrier and base, and means for moving said carrier over said keys.
2. In a stamping machine, a base, a co-operating pressure head, an interposed carrier, a series of independent pressing keys between said carrier and base, means for moving said carrier over said keys, and a type holder yieldingly carried by the base beneath said keys.
3. In a stamping machine, a base, a co-operating pressure head, an interposed carrier, a series of independent pressing keys between said carrier and base, means for moving said carrier over said keys, and

bearing rollers upon said carrier engaging said head and keys.

4. In a stamping machine, a base, a co-operating pressure head, an interposed carrier, a series of independent pressing keys between said carrier and base, means for moving said carrier over said keys, and means for adjusting said head relative to the carrier and the latter toward and from the base.

5. In a stamping machine, a base, a co-operating pressure head, cross heads at opposite sides of the base for supporting said pressure head, means for adjusting the cross heads upon the base, pressing keys supported above the base, and a carrier interposed between said keys and the pressure head.

6. The combination as in claim 5 with a feeding screw mounted in the cross heads and connected to said carrier.

7. The combination as in claim 5, means for adjusting the pressure head upon the cross head, and a yielding type holder disposed beneath said keys.

8. In a stamping machine, a base, a pressure head supported above the same, a pressing plate provided with loosely mounted keys, and a carrier having rolling contact with the pressure head and keys.

9. The construction of stamping machine defined by claim 8 with a type holder supported upon the base, and yielding means for supporting the keys above said type holder.

10. In a stamping machine, a base, a type holder yieldingly mounted thereon, a pressure plate having independently mounted movable keys yieldingly mounted above said type holder, a pressure head, and a carrier engaging said head and pressure plate in its movement.

11. The combination as in claim 10, with the cross heads supporting a feed shaft for the carrier and having screws for adjusting the pressure head relative to the carrier, and independent screws at the cross heads for adjusting the carrier relative to the pressure plate.

EDMOND CAUDRELIER.
